UNITED STATES PATENT OFFICE.

WARD RISLEY, OF JACKSBORO, TEXAS.

REFUSE-CREMATORIAL.

SPECIFICATION forming part of Letters Patent No. 674,319, dated May 14, 1901.

Application filed December 15, 1900. Serial No. 39,989. (No model.)

To all whom it may concern:

Be it known that I, WARD RISLEY, a citizen of the United States, residing at Jacksboro, in the county of Jack and State of Texas, have 5 invented certain new and useful Improvements in Refuse-Crematories; and I do hereby declare the following to be a full, clear, and exact description of the invention, such as will enable others skilled in the art to which 10 it appertains to make and use the same.

My invention relates to crematories or furnaces for burning garbage and other matter; and it consists of the novel structure and combination of parts hereinafter more particularly described and claimed.

Referring to the accompanying drawings, which illustrate a form of my invention, Figure 1 represents a vertical central sectional view of the crematory with parts shown in 20 elevation broken away. Fig. 2 is a transverse vertical sectional view of the same. Fig. 3 represents a section taken along the line 3 3, Fig. 1. Fig. 4 represents a section taken along the line 4 4, Fig. 1. Fig. 5 represents a section 25 taken along the line 5 5, Fig. 1.

Similar letters refer to similar parts throughout the several views.

My improved crematory or garbage-burner comprises, among other parts, a combined furnace and garbage-chamber A, the walls of 30 which are composed, preferably, of fire-brick or tile *a*, inclosed in a cast-iron casing *B*, which latter is held together by the rods *b*. In the lower part of the furnace or garbage-chamber are the fire-grates *C*, *C'*, and *C''*, into 35 which lead the fuel-openings *c*, *c'*, and *c''*. These fire-grates are closed in by the transverse tiles *c³*, *c⁴*, and *c⁵*, the tile *c⁴* extending higher than the others.

40 At about the center of the chamber A is a garbage-grating comprising a series of tubular cross-bars *D*, mounted upon rods *d*. These bars extend across the chamber, as shown most clearly in Fig. 2, and the grating which 45 they form extends almost the entire length of the chamber and near the forward end takes an upward curve, as at *d'*, to prevent garbage from falling off the grate into the passage leading to the chimney. The bars of this 50 grate are close together, but do not touch each other. The grating over the fire-grate *C* is separated from the rest by the tile *c⁴*.

In the bottom of the chamber A and extending almost the entire length thereof is an evaporating-pan *E*, preferably semicircular, or approximately so, in cross-section and closed at its ends. A flange *e* extends around the upper edge of this pan and supports it by resting upon the flanges *b'*, formed upon the lower edge of the iron casing *B*, and a flanged support *b''*, which also supports the tile *c³*. The end of the evaporating-pan beneath the fire-grate *C* is covered by means of a removable plate *e'*, which rests on the end of the pan and upon a flanged support *b³*, the latter 65 supporting also the tile *c⁴*.

In the brick housing *F* are the stoking-doors *G G*, which communicate by passages *g g* with the inside of the chamber. A door *G'* and passage *g'* open into the lower part of 70 the chamber for the admission of a device for stirring or agitating the contents of the evaporating-pan.

A brick housing *F* incloses the roasting-chamber *A* and is located at a sufficient distance from the outer iron casing of the said roasting-chamber to form a chamber in which air may be heated by radiation from the roasting-chamber and utilized for any desired purpose, such, for example, as heating feed-water for steam-boilers, heating buildings, &c. It will thus be seen that by this arrangement the same fire that is used for destroying the garbage and other refuse may be used for heating purposes. This heated air surrounding the chamber *A* may be conducted off to any desired point by the flue or duct *F'*. The hot-air space surrounding the furnace proper furthermore acts as a jacket and prevents loss of heat by radiation and at the same time 80 acting to heat the lower ends of the charging-tubes, which will cause to be burned or removed material that would have a tendency to stick to that part of said tubes were they not kept hot. Moreover, by thus creating a 85 heated zone through which the garbage passes just prior to reaching the furnace the garbage may be more quickly and readily burned. The foul gases and gases of combustion do not pass into the chamber which surrounds the 90 roasting-chamber *A*, but pass directly from the bottom of that chamber through the duct *i* into the chimney *I*, located to one side of the housing, as shown, so that the interior of the

roasting-chamber is entirely cut off from the chamber which surrounds it. The admission of cold air into the hot-air space or chamber between the brick housing and the roasting-chamber is regulated by the damper J. Access to the bottom of the furnaces is afforded by the door K.

The garbage or other refuse is charged into the crematory through a number of charging-tubes. In the drawings I have shown three of these, L, L', and L², which pass from a desired point above the housing F through it into the chamber A. I have represented a platform M above the furnace, upon which platform the garbage to be burned may be dumped, or this platform may represent any floor in the building with which the furnace or crematory is used. The upper end of the charging-tube L is flanged, as at l, where it engages the platform and is provided with a removable cover l'. Into this tube is charged the dry refuse, while the more moist or liquid portions are charged into the tubes L' and L². The tubes L' and L² are provided with removable extensions l' and l², respectively. In the lower ends of these extensions are pivoted the bowls N N', which are adapted to rotate on the spindles n n', respectively. These spindles are connected by arms n² and n³, respectively, to the levers n⁴ and n⁵, which are in turn pivotally connected at their upper ends to the hinged covers n⁶ n⁷, which close the tops of the tubes L' L².

O O' represent two flushing-tanks located above the tubes L' and L², respectively, one of said tanks being on each side of a partition P. The pipes Q Q' connect the tanks O O' with the upper extensions of the tubes L' and L², respectively, the said pipes discharging the water from said tanks into the tubes or bowls. Each of these tanks is provided with a float R, which is connected by means of a spring r and bolt r' with one end of a lever S, fulcrumed to the top of the tank. To the bottom of the float is secured one end of a pivoted arm T, which carries upon its other end a valve t, which is adapted to close an opening t', into which passes the water-supply pipe t'. The flow of the water from the tank into the pipes Q Q' is controlled by valves U, each secured to one side of a pivoted arm u, mounted in the flushing-tanks. The other end of each of the said arms u being connected by links u' to the lever-arms S. The ends of the levers S opposite the end connected to the floats are connected by rods V V' to the short arms v v', respectively, which latter are in turn made fast to the covers n⁶ n⁷, respectively.

While furnaces may be constructed as above described upon a large scale for burning the ordinary garbage collected from cities or towns, the crematory herein described is especially well adapted for use in burning the refuse from water-closets of jails and other public buildings or private dwellings which have no sewer connections. In such cases

the refuse from the water-closet bowl would instead of being discharged into a sewer be discharged into one or both of the tubes L' L². When used to burn the refuse from water-closets, the hinged tops upon the tubes would be employed as covers upon the seats of the closets, and the flushing device described would be that used with the closets, or any other suitable flushing devices may be used. Obviously when the crematory is used in such cases as this the closets would be located far enough away from the furnace to avoid the heat, and the ordinary garbage and refuse from the house would be deposited in the tube or opening L.

The operation of the device is as follows: Assuming that fires are burning in the grates C, C', and C², the garbage is dumped upon the grate D through the charging-tubes L, L', and L². In charging the dry refuse or garbage through the tube L all that is done is to remove the cover l' and dump the garbage or refuse into the tube, when it falls upon the grate and is consumed, as will be hereinafter more fully described, and when a sufficient quantity has been charged into the said tube the cover is replaced. In charging the more liquid garbage through the tubes L' L² it will have a tendency to adhere to the tube and accumulate there. To prevent this, I employ a flushing device such as herein shown and described, which insures a great degree of cleanliness, that could not otherwise generally be attained. When it is desired to charge the furnace through either of the tubes L' or L², these covers are raised, as shown in Fig. 1, where the cover n⁶ is supposed to open. When this is done, the bowl N assumes the position shown, its edge engaging a lug n⁸, which prevents it from turning too far. When the cover is thus raised, the lever-arm S will cause the float R to rise, which, acting through the arm T, will close the valve t to the supply-pipe and open the valve U, which will allow the water from the tank to pass out of the outlet-pipe Q and thence into the tube L' and bowl N. The garbage is then dumped into the tube, and when a sufficient quantity has been thus deposited the top of the tube is closed, which causes the bowl to dump to the position shown at N', when its contents will fall upon the grate. The closing of the cover of the tube also causes the valve U to close the outlet-pipe from the flushing-tank and the valve t to open the supply-pipe entrance into the tank, allowing the water to flow into the tank until the float rises to a sufficient level to bring the valve t upon its seat and close the end of the supply-pipe. The garbage falling upon the grating D will be consumed by the fires from below, while the noxious gases arising from the garbage will mingle with the products of combustion from the fires and be burned therewith before leaving the furnace. The products of combustion from the fire in the grate C will pass over the tiling c³ and around through the pas-

sage A' into the chimney I; but the gases and other products of combustion from the grates C' and C² will pass both beneath the grating D and then over it, when they will mingle with those from the grate C and pass together therewith into the chimney. The drippings from the more moist garbage will fall into the pan E, where they will be quickly evaporated, the vapors therefrom commingling with the gases from the fires and being consumed as they pass therewith through the furnace, as described. The heated gases passing beneath the evaporating-pan will keep it at a high temperature, and thus insure rapid evaporation.

Having thus described my invention, it is obvious that the same is capable of many modifications which might be made without departing from the spirit of the invention.

20 What I claim is—

1. A crematory for burning garbage and other refuse products, comprising a roasting-chamber, a grate within said chamber extending nearly the entire length of said chamber and adapted to receive and support the garbage, a plurality of fire-grates located beneath said grate, the products of combustion from some of said grates passing both beneath and over the top of said garbage-grate, while the products of combustion from the other of said fire-grates pass beneath a portion of said garbage-grate only, a charging-tube leading into the roasting-chamber above the fire-grate which delivers its products of combustion to only a part of the garbage-grate, charging-tubes leading into the roasting-chamber above the other of said fire-grates and above said garbage-grate, and means for conveying the burned gases away from said crematory, substantially as described.

2. A crematory for burning garbage and other refuse products, comprising a roasting-chamber, a grate within said chamber extending nearly the entire length of said chamber and adapted to receive and support the garbage, a plurality of fire-grates located beneath said grate, the products of combustion from some of said grates passing both beneath and over the top of said garbage-grate, while the products of combustion from the other of said fire-grates pass beneath a portion of said garbage-grate only, an evaporating-pan located beneath said grates, a charging-tube leading into the roasting-chamber above the fire-grate which delivers its products of combustion to only a part of the garbage-grate, charging-tubes leading into the roasting-chamber above the other of said fire-grates and above said garbage-grate, and means for conveying the burned gases away from said crematory, substantially as described.

3. A crematory for burning garbage and other refuse products, comprising a roasting-chamber, a grate within said chamber, extending nearly the entire length of said chamber and adapted to receive and support the garbage, a plurality of fire-grates located be-

neath said grate, the products of combustion from some of said grates passing both beneath and over the top of said garbage-grate, while the products of combustion from the other of said fire-grates pass beneath a portion of said garbage-grate only, an evaporating-pan located beneath said grates, a charging-tube leading into the roasting-chamber above the fire-grate which delivers its products of combustion to a part of the garbage-grate only, charging-tubes leading into the roasting-chamber above the other of said fire-grates and above said garbage-grate, means for flushing the latter charging-tubes, and means for conveying the burned gases away from said crematory, substantially as described.

4. A crematory for burning garbage and other refuse products, comprising a roasting-chamber, a grate within said chamber, extending nearly the entire length of said chamber and adapted to receive and support the garbage, a plurality of fire-grates located beneath said grate, the products of combustion from some of said grates passing both beneath and over the top of said garbage-grate, while the products of combustion from the other of said fire-grates pass beneath a portion of said garbage-grate only, an evaporating-pan located beneath said grates, a charging-tube leading into the roasting-chamber above the fire-grate which delivers its products of combustion to a part of the garbage-grate only, charging-tubes leading into the roasting-chamber above the other of said fire-grates and above said garbage-grate, and means for automatically flushing the latter charging-tubes, and means for conveying the burned gases away from said crematory, substantially as described.

5. A crematory for burning garbage and other refuse products, comprising a roasting-furnace, in combination with a housing inclosing said furnace and forming a hot-air chamber around the same, the said furnace and its passages being closed to said hot-air chamber, a grate within said furnace adapted to receive the garbage, a plurality of fire-grates beneath said grate, the products of combustion of some of said grates passing both beneath and over the top of said garbage-grate, while the products of combustion from the other of said fire-grates pass beneath a portion only of said garbage-grate, charging-doors for said fire-grates, charging-tubes leading into the furnace above the said fire-grates and above said garbage-grate, said tubes passing through said hot-air space, and means for conveying the products of combustion away from said furnace and the hot air from said hot-air chamber, substantially as described.

In testimony whereof I affix my signature in presence of two witnesses.

WARD RISLEY.
